UNITED STATES PATENT OFFICE.

HARVY BARRE CUNNINGHAM, OF ST. PAUL, MINNESOTA.

FIRE-PROTECTOR FOR MOVING-PICTURE-MACHINE MAGAZINES.

1,090,287.

Specification of Letters Patent. Patented Mar. 17, 1914.

Application filed July 31, 1911. Serial No. 641,687.

To all whom it may concern:

Be it known that I, HARVY BARRE CUNNINGHAM, a citizen of the United States, residing at St. Paul, in the county of Ramsey and State of Minnesota, have invented a new and useful Improvement in Moving-Picture Machines—namely, a Fire-Protector for Moving-Picture-Machine Magazines—of which the following is a specification.

10 This invention relates to a safety attachment for moving picture machine film magazines and has for its object to provide a means for either manually or automatically severing a strip of film which may have become ignited and to prevent the communication of flame to the interior of the film magazines.

I attain the general objects stated by the mechanism illustrated in the accompanying drawings, in which—

20 Figure 1, shows the attachment of the device to moving picture machine magazines; Fig. 2, a bottom view of the device; Fig. 3, a part of a moving picture machine, showing the attachment and position of the combustible fuse; Fig. 4 is a side view of a moving picture machine showing the attachment in place on the magazines.

Similar letters on the drawing refer to 30 similar parts throughout the several views.

Referring to Figs. 1 and 2 of the drawings, *j* represents a support comprising a rectangular frame-piece or casing which is adapted to be attached to a film magazine *Q* across the opening through which the film enters or makes its exit, as the case may be. This frame-piece has mounted therein, so as to flank the transverse axis of one face of the same, a pair of guide rollers *c*, and the 35 side walls adjacent the opposite face are provided with longitudinal guideways in which a pair of shear blades *g* are slidably mounted. These blades are adapted to be moved toward each other so that their cutting edges 40 overlap, thus shearing the film which passes between them when they are in their inoperative or normal positions. In addition to severing the film, the blades provide the additional function of serving to completely 45 close the opening into the magazine, in this manner effectually cutting off the communication of flame to the interior of the magazine.

The shear blades or knives *g* are provided 50 at the ends opposite the cutting edges with laterally bent portions which serve as han-

dle members whereby the blades can be operated manually. The blades can also be operated automatically by means of the spring *d* which is coiled about the stud *i*, supported 60 on the bracket *h* which projects from one side of the casing *j*. The coiled portion of the spring *d* is held clamped between washers *p* by means of an ordinary nut on the end of the stud *i*.

Affixed to each shear blade by means of a nut *o* is a stud *f*. These studs are engaged by the extended ends of the spring *d*. The ends of the spring *d* and consequently the shear blades, are normally held apart by the 70 engagement therewith of a pair of detent arms *a* which are pivoted to the casing one on either side of the bracket *h*. One end of each arm extends from the casing and alongside the magazine and has attached thereto 75 a branch of a combustible cord or fuse *e*. This member, which may be combustible or fusible throughout its length, or only between eye *b* and post *k*, as shown in Fig. 3, is passed through an eye *b* on the side of 80 the magazine just beyond the ends of the arms, so that, when the cord is drawn taut, the corresponding ends of the arms are held together, thus holding the opposite ends of the arms, and consequently the spring ends 85 and the shear blades, apart.

In ordinary practice, this combustible cord is led from each magazine through another eye *b* on the body or standard *n* of the machine and thence across the standard and 90 closely adjacent the aperture and film guide plate *m* to a stud on post *k* to which it is attached. It will be seen that, should the film strip become ignited, that portion of the combustible cord *e*, because of its proximity 95 to the film in its travel over the guide plate *m*, will at once ignite and be destroyed and the detent arms *a*, being no longer restrained, will allow the extended ends of the spring *d* to immediately actuate the shear blades *g* 100 to sever the film and close the opening to the magazine, thus cutting off the possibility of the communication of fire to the roll of film inside the magazine and confining the 105 damage to the comparatively short length of film which extends from one magazine to the other.

Having thus described my invention what I claim is:

1. A safety device for motion picture machines comprising a rectangular frame-piece provided with rectangular guideways, an 110

opening through the center of said frame-piece, cutting blades mounted to slide in said guideways, a spring engaging said cutting blades and tending to move them toward each other to cover said opening and to cause their cutting edges to overlap, combustible means normally holding said blades in retracted positions, said frame-piece being adapted for attachment to a film magazine with the opening therein in alinement with the opening in the magazine through which the film passes, whereby, upon the accidental ignition of said combustible means, said spring actuates said blades to sever the film and cover said opening substantially as described.

2. An attachment for motion picture machine magazines comprising a support, a pair of rollers mounted in said support and adapted to guide between them the film strip as it issues from the magazine, spring actuating flat shear blades slidably mounted in said support and tending to sever the film strip as it passes between said rollers and to cut off the communication of fire to the interior of the magazine, an inflammable cord normally holding said blades inoperative, said cord being arranged so that a portion of the same lies in proximity to the aperture of the projecting lantern, whereby, upon the ignition of the film as it passes said aperture, the adjacent cord will be severed to release the shear blades substantially as described.

3. In combination with the film aperture of a motion picture machine magazine, a rectangular casing with an opening in one face adapted to be placed in alinement with said aperture, slidable plates with shearing edges forming the opposite face of said cas-

ing, grooves in which said plates are slidably mounted, a bracket on one side of said casing, a post on the free end of said bracket, a spring mounted on said post so as to engage with its end portions said slidable plates, said spring tending to move said plates to cover said opening, detent arms pivoted intermediate their ends to the side of said casing which supports said bracket, one end of each arm adapted to engage an end portion of said spring, an inflammable cord attached to the opposite ends of said arms, said cord adapted to hold said arms in their spring retracting positions so that said opening is normally uncovered.

4. In combination with the film aperture of a motion picture machine magazine, a casing provided with an opening in one face adapted to be placed in alinement with said aperture, slidable shear plates with laterally bent portions forming the opposite face of said casing, a bracket attached to one side of said casing, a post on the free end of said bracket, a spring mounted on said post for engagement with said shear plates, said spring tending to move said plates to cover said opening and sever the film passing therethrough, detent arms pivoted to said casing and engaging said spring, a combustible cord engaging said arms to hold them in their spring retracting positions, whereby, upon combustion of the cord, or upon manual actuation of said laterally bent end portions, said shear plates will be moved to cover said opening and sever the film.

HARVEY BARRE CUNNINGHAM.
